UNITED STATES PATENT OFFICE.

STERLING ELLIOTT, OF NEWTON, MASSACHUSETTS.

STENCIL-CUTTING MACHINE.

No. 927,842.

Specification of Letters Patent.

Patented July 13, 1909.

Application filed May 7, 1908. Serial No. 431,519.

To all whom it may concern:

Be it known that I, STERLING ELLIOTT, of Newton, county of Middlesex, State of Massachusetts, have invented an Improvement 5 in Stencil-Cutting Machines, of which the following is a specification.

This invention relates to stencil-cutting machines and has for its object to arrange a stationary, circular, dial-plate in front of a 10 rotary tool-holder, and to provide a pointer which is movable over said dial-plate, and to provide hand-engaging means, such, for instance, as a ring which is accessible at opposite sides of said dial-plate, whereby it is 15 adapted to be engaged by both hands of the operator, and which is connected with said pointer and tool-holder for operating them simultaneously, and to provide means for operating the tools carried by the tool- 20 holder; also to arrange said stationary unobstructed dial-plate in an inclined position and to correspondingly arrange the pointer and pointer-shaft and means for operating it; also to provide a driving-gear on the shaft carrying 25 the pointer which engages a driven-gear on the shaft carrying the tool-holder and to attach to the driving-gear a hand-engaging ring by which it may be turned to thereby turn the pointer-carrying shaft and the tool- 30 holder simultaneously; also to provide an improved form of bearing for the pointer-carrying shaft; also to provide an improved form of locking-device for the tool-holder whereby the tool-holder may be firmly held 35 against rotary movement when engaged by it and to provide the foot-lever which is employed for operating the tool-actuating device, with means for moving said locking-device into its unlocking position and to provide means independent of the foot-lever for 40 operating said locking-device to move it into its locking position.

Figure 1 is a front view of a stencil-cutting machine embodying this invention. Fig. 2 45 is a vertical section of the head of the machine taken on the dotted line 2—2 Fig. 1. Fig. 3 is a plan view of the machine, the plunger and operating mechanism therefor being omitted. Fig. 4 is a detail showing the locking device for the tool-holder in engaging position therewith. Fig. 5 is an enlarged detail of the locking detent and a portion of the toothed gear which it engages. Figs. 6 and 7 50 are details of portions of the toothed gears which are connected with the pointer and tool-holder.

a represents a tool-holder, which may be employed in carrying out this invention. It is herein shown as cylindrically formed and provided with a circularly arranged series of 60 holes near its edge which receive punching tools *a'* of any suitable construction, which are adapted to cut the stencil. These tools are normally lifted by springs *a''* and adapted to be depressed by means of a plunger *b*, 65 beneath which they are brought as the tool-holder is turned. The tool-holder is secured to the upper end of an upright shaft *a'* having its bearings in the main frame of the machine. Said shaft *a'* has secured to its lower 70 end a toothed gear *c* which is engaged and driven by a toothed gear *c'* secured to the lower end of a shaft *d*. The shaft *d* extends up through the center of a circular dial-plate *d'* which is stationarily supported on a forward extension of the main frame of the machine in front of the tool-holder. The dial-plate is preferably arranged in an inclined 75 position to better enable the operator to observe the characters thereon, and consequently the shaft *d* is inclined to the perpendicular, being arranged at right angles to the plane of the dial-plate and the toothed gear *c'* is also inclined, being arranged in parallelism with the dial-plate. 80

To the upper end of the shaft *d* a pointer *d''* is secured which moves over the face of the dial-plate, and the means herein shown for attaching the pointer to the shaft are arranged to also provide a ball-bearing for the 90 shaft in order that it may be turned freely. Said attaching means consists of a circular cap *d'''* bearing the pointer and made of suitable size to fit loosely upon or embrace the hub *d''*, formed on the upper side of the dial-plate, so as to turn thereon. This cap is attached to the shaft *d* and as herein shown the shaft has a screw-threaded stud *d''''* rising from it which extends through a center-hole in the cap, and a nut *d''''* is screwed onto said 100 stud which holds the cap securely on the shaft. The shaft *d* extends a short distance above the end of the hub *d''*, and around said shaft a set of balls *d''''* is arranged, said balls being held in place between the cap and the 105 end of the hub. The weight of the toothed gear and shaft is, therefore, borne by the balls and consequently said balls serve as a ball-bearing to permit the shaft to be easily turned. A ring *e* is secured to the toothed 110 gear *c'* which is made larger in diameter than the dial-plate, and the perimeter of said ring

is shaped so as to be conveniently engaged by both hands of the operator for the purpose of turning it and thereby turning the gear c' and parts connected therewith, as for 5 instance, the pointer and tool-holder. The ring e being made larger in diameter than the dial plate and arranged at the side of and preferably in a plane below said plate may be conveniently engaged by both hands 10 of the operator and turned while he watches the pointer move over the face of the dial plate and the view of said dial-plate is not obstructed. It will be observed that the circular tool-holder bearing a large number 15 of tools is quite heavy, yet it may be easily turned together with the pointer by the hand-engaging means herein shown, the operator using both hands in performing this work. Furthermore, by arranging the hand- 20 engaging means as herein shown, so that it is accessible at opposite sides of the dial-plate, it may be engaged by both hands of the operator and the dial-plate disposed between the hands of the operator so as to 25 be very conveniently observed. The tools are arranged in the tool-holder to correspond with the position of the characters on the dial-plate so that the relative position of the tools may be determined by watching the 30 movements of the pointer.

The teeth of the gears c and c' are beveled to accommodate their relative angular positions with respect to each other. Furthermore, the teeth of the driven gear c are made 35 quite long and taper toward their ends to provide for the operation of a centering-device which also serves as a means for locking the gear in fixed position. The tapering sides of the teeth provide for engagement 40 therewith of the locking-detent which operates to move the gear a little either way to thereby bring the tool directly beneath the plunger.

Referring to Fig. 5, the extra long tapering teeth are shown together with the locking-detent, the sides of the teeth continuing to taper almost to the ends thereof being thereby formed almost to a point. The interdental spaces in the driven gear c' are 50 shaped to accommodate said extra long tapering teeth of the driven gear, as shown in Fig. 7. f represents the locking-detent, which is secured to the upper end of an arm f' secured to a pivot-shaft f^2 having its bearings in the main frame. Said detent is made as a tapering or wedge-shaped tooth adapted 55 to enter any one of the spaces between the teeth of the driven gear c , and if said gear is not correctly disposed relative to said de- 60 tent, said detent will engage one or the other side of one of the teeth thereof, and will move said gear a little in one or the other direction as it enters the space. Therefore, the locking-detent serves both as a locking means for 65 the gear and as a centering means. The

pivoted arm f' is moved into engagement with the driven gear by a spring f^3 which is attached to it and to the frame, when said spring is permitted to act, and is moved out of engagement positively by means provided 70 for the purpose. By providing a spring or other independent means for moving the locking-detent into locking position, its movement is the same at each operation and such movement may be regulated to suit the conditions. An arm f^4 is secured to the pivot-shaft f^2 which extends rearward and has an enlarged end, and an arm f^5 also having an enlarged end is arranged on a lever g , which is adapted to engage said arm f^4 and depress it, 75 and thereby rock the pivot-shaft f^2 bearing the locking-detent so as to move said detent into unlocking position or out of engagement with the gear. The lever g herein provided for moving the arm f^5 is pivoted to the main 80 frame at g' and extends downward and is provided at its lower end with foot-engaging studs, in order that it may be swung on its pivot by the action of the feet of the operator. It is moved rearward positively by the pressure of the feet of the operator and forward by gravity when pressure upon it is relieved. When said swinging-lever is moved rearward the arm f^5 disengages the arm f^4 , and the locking-detent thus released is moved into 85 locking position by the action of the spring f^3 , and when said lever is returned to its normal position the arm f^5 again engages said arm f^4 and rocks the pivot-shaft and moves the locking-detent into its unlocking position. The locking device is released during 90 the first part of the rearward movement of the operating-lever g and is immediately operated by the spring or other independent means employed for operating it. The locking-detent will be released for the purpose of locking the gear when the tool-holder has been moved into correct position or approximately correct position to bring one of the 95 tools beneath the plunger b which will be determined by the movements of the pointer, and, as it is at this time that the plunger is 100 designed to operate the tool, the said lever g is or may be also employed as a means for operating it, but the invention is not limited to thus employing the lever g , for this purpose, as its particular function, so far as the present invention is concerned, is to control the action of the locking-detent. By so arranging the parts that the operating-lever releases the centering and locking device during the first part of its rearward movement, the plunger may be subsequently operated during the latter part of said rearward movement. Rearward movement of the 110 lever g is limited by a stop arm g^2 engaging a yielding stop g^3 on the frame, and forward movement of said lever is limited by the body portion of the lever engaging a yielding stop g^4 on the frame. The lever g has at its upper 115

100

105

110

115

120

125

130

end an upwardly extended arm g^5 bearing a roll g^6 which engages the end portion of an arm g^7 bearing a plunger b . Said arm is pivoted at b^2 to the frame and extends forward 5 and supports the plunger above the tools and above the bed h on the frame, and when said arm is depressed by the movement of the lever g the plunger will engage one of the tools and force it downward toward the bed. The 10 arm bearing the plunger is raised by a spring b^3 . The plunger b may be adjustably supported at the outer end of the arm b' in any suitable manner.

In the machine herein shown, a movable 15 bed strip i is employed which passes over the bed h and which is fed along intermittently by means of suitable feeding-rolls i' and i'' , or by other suitable means provided for the purpose.

20 Having thus described my invention, what I claim as new and desire to secure by Letters Patent is:—

1. In a stencil-cutting machine, the combination of a rotary tool-holder, a stationary 25 unobstructed circular dial-plate located in front of said tool-holder, a pointer movable over the dial-plate, hand-engaging means arranged at both sides of said dial-plate whereby it is adapted to be engaged by both hands 30 of the operator, which is connected with said pointer and tool-holder for operating them simultaneously, and means for operating the tools carried by said tool-holder, substantially as described.

35 2. In a stencil-cutting machine, the combination of a rotary tool-holder, a stationary unobstructed circular dial-plate located in front of said tool-holder, a pointer movable over the dial-plate, a shaft bearing the pointer 40 extending through the dial-plate, a ring located adjacent the dial-plate and accessible at opposite sides thereof, whereby it is adapted to be engaged by both hands of the operator, and means connecting said ring 45 with said pointer-shaft and also with said tool-holder for operating them simultaneously, and means for operating the tools carried by said tool-holder, substantially as described.

50 3. In a stencil-cutting machine, the combination of a rotary tool-holder, a stationary unobstructed dial-plate located in front of said tool-holder, a pointer movable over the dial-plate, a hand-engaging ring, made 55 larger in diameter than the dial plate, means connecting it with said pointer and also with said tool-holder for operating them simultaneously, and independent means for operating the tools carried by said tool-holder, 60 substantially as described.

4. In a stencil-cutting machine, the combination of a rotary tool-holder, a stationary unobstructed dial-plate located in front of 65 said tool-holder, a pointer movable over the dial-plate, a hand-engaging ring, arranged

in a plane below the dial-plate, and connected with said pointer and tool-holder for operating them simultaneously, and independent means for operating the tools carried by the tool-holder, substantially as described. 70

5. In a stencil-cutting machine, the combination of a tool-holder, a shaft bearing it, a driven-gear on said shaft, a stationary dial-plate, a pointer movable over the dial-plate, a shaft bearing said pointer extending down 75 through the dial-plate, a driving-gear secured to said shaft beneath the dial-plate, and engaging said driven-gear, a hand-engaging ring secured to said driving-gear, and independent means for operating the tools 80 carried by said tool-holder, substantially as described.

6. In a stencil-cutting machine, the combination of a tool-holder, a shaft bearing it turning on a vertical axis, a driven gear on 85 said shaft, a stationary dial-plate disposed in inclined position, a pointer movable with respect thereto, an inclined shaft bearing said pointer, a driving-gear thereon engaging said driven-gear, means for turning said 90 gears to turn said shafts simultaneously, and independent means for operating the tools carried by said tool-holder, substantially as described.

7. In a stencil-cutting machine, the combination of a stationary dial-plate having a center hub, a shaft extending through said hub, a cap secured to said shaft, a set of balls arranged about the shaft between the cap and the ends of the hub, a pointer extended 100 from said cap, a tool-holder, a shaft bearing it, and means connecting said tool-holder shaft with said pointer-shaft, whereby they are turned simultaneously, and means for turning them, substantially as described. 105

8. In a stencil-cutting machine, the combination of a tool-holder, a shaft bearing it turning on a vertical axis, a driven-gear on 110 said shaft, a stationary dial-plate located in front of said tool-holder, a pointer movable with respect thereto, a shaft bearing said pointer, a driving-gear thereon engaging said driven-gear, hand-engaging means for turning said gears to turn said shafts simultaneously, a locking-detent for engaging the 115 teeth of one of said gears, a tool-actuating-device, and a foot-lever arranged to control the operation of said locking-detent and also operate said tool-actuating-device, substantially as described.

9. In a stencil-cutting machine, the combination of a rotary tool-holder, a tool actuating-device, a stationary dial-plate located in front of said tool-holder, a pointer movable over the dial-plate, hand-engaging 125 means connected with said pointer and tool-holder for operating them simultaneously, a locking-device for the tool-holder, a foot-lever, arranged to operate said tool-actuating-device, having means for moving said 130

locking-device into its unlocking position when moved in one direction and to release it when moved in the other direction, and means independent of the foot-lever for 5 moving said locking-device into locking position when released by said foot-lever, substantially as described.

10. In a stencil-cutting machine, the combination of a rotary tool-holder, a tool actuating-device, a stationary dial-plate located in front of said tool-holder, a pointer movable over the dial-plate, hand-engaging means connected with said pointer and tool-holder for operating them simultaneously, a 15 locking-device for the tool-holder, a foot-lever normally engaging said locking-device for successively releasing said locking-device and for operating said tool-actuating-device, and means independent of the foot-lever for 20 moving said locking-device into locking position when released, substantially as described.

11. In a stencil-cutting machine, the combination of a rotary tool-holder, hand-operated means for turning it, a locking-device 25 for said tool-holder, a foot-lever, engaging means thereon for the locking-device, whereby said locking-device is moved into its unlocking position by the foot-lever, and is subsequently released, and a spring for moving 30 said locking-device into its locking position when released by said foot-lever, substantially as described.

12. In a stencil-cutting machine, the combination of a rotary tool-holder, hand-operated means for turning it, a spring-pressed locking-device for said tool-holder, means for moving said locking-device into its unlocking position and for normally holding it in such position which is movable to release 40 it permitting it to operate, substantially as described.

13. In a stencil-cutting machine, the combination of a rotary tool-holder, hand-operated means for turning it, a spring-pressed locking-device for said tool-holder, means for moving said locking-device into its unlocking position and for normally holding it in such position which is movable to release it permitting it to operate, and a tool-actuating 45 device connected with and operated by the aforesaid means, arranged to operate the tool

after the locking-device has been released, substantially as described.

14. In a stencil-cutting machine, the combination of a tool-holder, a shaft bearing it, a driven-gear on said shaft, a stationary dial-plate, a pointer movable with respect thereto, a shaft bearing said pointer, a driving-gear thereon engaging said driven-gear and means for turning said gears to turn said shafts 60 simultaneously, a pivoted locking-detent for engaging the teeth of said driven-gear having an engaging portion, a spring for moving it into locking position, and a lever having an engaging-portion for engaging the engaging-portion of said detent to move it into its unlocking position, substantially as described. 65

15. In a stencil-cutting machine, the combination of a tool-holder, a shaft bearing it, a driven-gear on said shaft having long pointed 70 teeth, a stationary dial-plate, a pointer movable with respect thereto, a shaft bearing said pointer, a driving-gear on said shaft having deep interdental spaces to receive the teeth on said driven-gear, means for turning 75 said gears to turn the shafts simultaneously, a locking-detent for engaging the driven-gear, a spring for moving it into locking position, and a lever for engaging it and moving it into unlocking position, substantially as 80 described.

16. In a stencil-cutting machine, the combination of a tool-holder, a shaft bearing it, a driven-gear on said shaft having long pointed teeth, a stationary dial-plate, a shaft bearing said pointer, a driving-gear on said shaft having deep interdental spaces to receive the teeth on said driven-gear, means for turning 85 said gears to turn the shafts simultaneously, a detent adapted to engage the teeth of one of said gears for centering and locking it, and means for operating said detent, substantially as described. 90

In testimony whereof, I have signed my 95 name to this specification, in the presence of two subscribing witnesses.

STERLING ELLIOTT.
